UNITED STATES PATENT OFFICE

EARL H. HOWARD, OF LOS ANGELES, CALIFORNIA, ASSIGNOR TO ELECTRO-THERAPY PRODUCTS CORPORATION, LTD., OF LOS ANGELES, CALIFORNIA, A CORPORATION OF DELAWARE

DESIGN FOR A HANDLE FOR THERAPEUTIC LAMPS

Application filed May 2, 1932. Serial No. 43,697. Term of patent 7 years.

To all whom it may concern:

Be it known that I, EARL H. HOWARD, a citizen of the United States, residing at Los Angeles, in the county of Los Angeles and State of California, have invented a new, original, and ornamental Design for a Handle for Therapeutic Lamps, of which the following is a specification, reference being had to the accompanying drawing forming a part thereof, wherein

Figure 1 is a front elevational view of a handle illustrating my design;

Figure 2 is a side elevational view, illustrating my design;

Figure 3 is an end elevational view, look-

ing from the tube end of a handle embodying my design;

Figure 4 is a sectional view taken along line IV—IV of Figure 1;

Figure 5 is a partial detail view illustrating a section taken along line V—V of Figure 1; and

Figure 6 is a partial sectional view, taken along line VI—VI of Figure 1.

I claim:

The ornamental design for a handle for therapeutic lamps, as shown.

Signed at Los Angeles, California, this 25th day of April, 1932.

EARL H. HOWARD.
